MATERIALS HANDLING CONTAINER

Charles C. Averill, Albion, Mich., assignor to Union Steel Products Company, Albion, Mich.

Application November 26, 1954, Serial No. 471,413

8 Claims. (Cl. 220—97)

This invention relates to improvements in walled materials handling pallets which may be stacked for shipping and are well adapted to withstand the shocks normally occurring in transportation.

The main objects of this invention are:

First, to provide a walled materials handling pallet which may be stacked and the stacked pallets secured together in stacked relation so that they effectively withstand the shocks such, for example, as are incident to railway transportation.

Second, to provide means for locking a superimposed walled pallet upon a supporting pallet which while effective for the purpose permits the ready release of the superimposed pallet.

Third, to provide a leg structure which is capable of sustaining heavy loads and at the same time is of relatively light weight.

Objects relating to details and economies of the invention will appear from the description to follow. The invention is defined and pointed out in the claims.

A preferred embodiment of the invention is illustrated in the accompanying drawing, in which:

Fig. 1 is an end elevational view of a pallet embodying my invention with certain wall parts broken away and sectioned to show structural details.

Fig. 2 is a fragmentary side elevational view viewed from the left of Fig. 1.

Fig. 3 is a fragmentary side elevational view partially in section on a line corresponding to line 3—3 of Figs. 4 and 5 and with other parts broken away to show structural details.

Fig. 4 is a fragmentary perspective view showing details of the deck bed and one of the legs provided with a locking dog.

Fig. 5 is a fragmentary view partially in horizontal section on a line corresponding to the broken line 5—5 of Fig. 4.

Fig. 6 is a fragmentary view in section on a line corresponding to line 6—6 of Fig. 3.

Fig. 7 is a fragmentary plan view partially in section illustrating details of the pallet structure and also a modified form of locking dog.

Fig. 8 is a fragmentary view partially in section showing further details of the locking dog of Fig. 7.

Fig. 9 is an end elevation of a leg formed as an integral casting with a modified form of mounting for the locking dog.

The embodiment of my invention illustrated is especially adapted for use as a shipping pallet, for example, pallets to be loaded and placed in freight cars in stacked relation. Freight cars are subject to severe shocks in switching, coupling and the like, which shocks tend to shift loaded pallets in the car and to shift stacked pallets relative to each other. One of the objects of my invention is to provide means for maintaining the stacked pallets in their stacked relation to each other.

In the embodiment illustrated the pallet deck design-

2

nated generally by the numeral 1 comprises an upper series of rod like slats 2 disposed in spaced parallel relation and a lower series of slats 3, similarly disposed in spaced parallel relation and in crossing relation to the upper series of slats and fixedly secured thereto at their crossing points by welds indicated at 4. This form of grid-like deck is old.

The deck is provided with a deck bed comprising side members 5 desirably of upwardly facing channel section and cross members 6 also desirably of upwardly facing channel section. The lower series of slats are disposed in crossing relation to the side bed members 5 and fixedly connected thereto as by welds 7 to the upper edges of the flanges. The upper edges of the cross bed member 6 project above the upper edges of the side members 5, in supporting relation to intermediate slats of upper series which are welded thereto as indicated at 8.

The inner flanges of the side sill members have openings 9 therein in which the ends of the cross members are disposed. The legs designated generally by the numerals 10 and 11 are the same in structure with the exception that the legs 10 are provided with locking dogs 12 for purposes which will be described later. Preferably there are opposed pairs of legs 10 at one end of the structure. The leg structure is such that they may be readily fabricated from plate stock.

The legs 10 and 11 comprise top members 13 and bottom members 14 connected by outer and inner uprights 15 and 16. The bottom members have upwardly offset portions 17 which coat with the lower ends of the uprights 15 to form downwardly facing stacking recesses. The top members are provided with upwardly projecting flanges 18 and with upwardly projecting lugs 19 and 20. The lug 19 is spaced from the flange 18 to receive the bed side member between them.

The legs 19 and 20 are laterally offset relative to each other to engage opposite sides of the cross bed members 6. The lug 19 is positioned at one edge of the opening in the inner flange of the bed member 5 and is welded to the side of the cross members 6, as indicated at 21, the lug 20 being welded to the other side as indicated at 22. This provides a very rigid connection for the legs and bed members which is of importance as the structures are subjected to very severe stresses in use.

It is desired to point out however, that in factory warehouses and the like it is also a matter of advantage to lock the pallets in stacked relation to prevent accidental displacement, such as might result from the shock of forcible contact with a pallet of an adjacent stack as the pallets are being stacked or a pallet removed from a stack.

As I have pointed out the foregoing description applies to legs 10 and also to the legs 11. However, as stated, the legs 10 are provided with the locking dogs 12 which in the preferred embodiment are pivotally mounted on the pins 23 disposed through the front upright and a post 24 provided to support the inner end of the pin. The pin is arranged through a hole 25 in the front upright and is desirably secured by means of a weld 26. The purpose of this being that if repair is required the weld may be ground off to release the pin at the same time the pin is securely retained. The pin is arranged through the dog at 27. The coil spring 28 on the pin yieldingly urges the dog against the front upright which is provided with a fixed detent 29 coacting with the recess like keeper 30 in the dog when the dog is in its retracted or elevated position to hold it in that position.

The side walls 31 are provided with holders 32 and 33, the holders having upwardly projecting hooks 34 facing in the same direction. These holders 32 and 33 are the same with the exception that the holders 32 are provided with keepers 35 with which the locking dogs

12 coat when one pallet is superimposed upon another with the legs of the superimposed pallet engaged with the hooks of the holders.

In the embodiment illustrated the side walls 31 are provided with inwardly projecting hinge arms 36 at their lower ends connected by the hinge rods 37 which are hingedly connected by the coils 38 to the adjacent deck members 39.

The end walls 40 are provided with downwardly projecting lugs 41 at their lower ends and have vertically spaced locking bolts 42 engageable with keepers 43 at the ends of the side walls. This permits the removal of at least one end wall. However, these features form no part of my present invention. The side walls 31 are desirably provided with a pair of top bars 44 to which the holders 32 are fixedly secured, as by the welds 45, see Fig. 6.

In the embodiment shown in Fig. 7 the legs 46 which correspond to the legs 10 are provided with a transverse wall 47 to which the pivot blocks 48 for the pivot 49 is secured.

In this embodiment the dog 50 is disposed transversely of the holders having the keepers. The embodiment previously described is preferred however as the dog is mainly housed within the leg. The dog 50 is slotted at 51 to permit pivotal end sliding movement thereof so that the dog may be swung upwardly and shifted longitudinally to engage with the stop 52 for holding the dog in retracted position, as shown by dotted lines in Fig. 8. The stop 53 limits the downward swing of the dog so that it does not swing below the bottom of the leg. However, the stop 53 is positioned so that the dog effectively engages behind the keeper 35.

In the embodiment shown in Fig. 9 the leg designated generally by the numeral 54 has the same general contour and features as the legs previously described, but is formed as a casting. In this embodiment the pin 55 corresponding to the pin 23 is supported at its inner end by an internal boss 56 and is retained therein by the locking pin 57.

In the embodiment illustrated the deck is preferably provided with spaced parallel bars 58 on which the heavy material may be disposed. These serve as reinforcing bars for the deck and also as supports for finished parts which might be abraded by contacting with the grid deck.

To prevent injury of the grid walls such as might result by contacting with interior parts of a freight car or the like the side walls are provided with guard bars or rails 60 desirably of inwardly facing channel section and fixedly secured in horizontal position to the outer sides of the vertical slats of the side walls. These guard rails also project beyond the end edges of the end walls and serve both to guard the sides and end walls.

I have illustrated and described my invention in a highly practical commercial embodiment thereof. I have not attempted to illustrate or describe various adaptations and modifications which I contemplate as it is believed this disclosure will enable those skilled in the art to embody or adapt my invention as desired.

Having thus described the invention, what is claimed as new and is desired to be secured by Letters Patent is:

1. In a walled materials handling pallet, the combination of a deck bed provided with walls and comprising side members and cross members extending between the side members, the side members being of upwardly facing channel section and having opening in their inner flanges, a deck mounted on and fixedly secured to said deck bed members, legs comprising top members having upwardly projecting flanges adjacent their outer sides and upwardly projecting lugs spaced laterally from the flanges and relative to each other, said deck side members being disposed on said leg top members between the flanges and adjacent lugs and fixedly secured thereto, the deck cross members being disposed in said openings in said inner flanges

of said deck side members and between said pairs of lugs of the top leg members and fixedly secured thereto, at least one of the legs having a locking dog pivotally mounted thereon for vertical swinging movement, a detent for holding said dog in retracted position, and stacking holders on opposed walls adapted to receive the legs of a superimposed pallet and provided with leg engaging hooks facing in the same direction and with which the legs of a superimposed pallet may be slidably engaged, at least one holder member of each pallet being provided with a keeper with which the locking dog of a superimposed pallet may be engaged and thereby prevent sliding disengagement of the legs from the hooks of said stacking holders.

2. In a walled materials handling pallet, the combination of a deck bed provided with walls and with legs having downwardly facing stacking recesses, at least one of the legs having a locking dog pivotally mounted thereon for vertical swinging movement, a detent for holding said dog in retracted position, and stacking holders on said walls adapted to receive the legs of a superimposed pallet and provided with leg engaging hooks facing in the same direction and with which the legs of a superimposed pallet may be slidably engaged, at least one holder member of each pallet being provided with a keeper with which the locking dog of a superimposed pallet may be engaged and thereby prevent sliding disengagement of the legs from the hooks of said stacking holders.

3. In a walled materials handling pallet, the combination of a deck bed provided with walls and with legs having downwardly facing stacking recesses, at least one of the legs having a locking dog, a detent for holding said dog in retracted position, and stacking holders on and projecting above said walls and adapted to receive said and slidably support the legs of a superimposed pallet and provided with laterally facing leg engaging hooks with which the legs of a superimposed pallet may be engaged by a lateral sliding movement of the superimposed pallet, at least one holder member of each pallet being provided with a keeper with which the locking dog of a superimposed pallet may be engaged and thereby prevent sliding disengagement of the legs from the hooks of said stacking holders.

4. In a walled materials handling pallet, the combination of a deck provided with walls, legs comprising spaced top and bottom members and laterally spaced inner and outer uprights integral therewith, the bottom members having downwardly facing stacking recesses therein, at least one of the legs having a post disposed in laterally spaced relation to its outer upright, a locking dog disposed between and pivotally mounted on the post and the upright for vertical swinging movement, a detent for said dog disposed on the inner side of the upright for holding said dog in retracted position, said dog having a keeper recess coacting with said detent, and upwardly facing stacking holder members on opposed walls adapted to receive the legs of a superimposed pallet and provided with hooks facing in the same direction and with which the legs of a superimposed pallet may be engaged, at least one holder member of each pallet being provided with a keeper with which the locking dog may be engaged and thereby prevent disengagement of the legs from the hooks of said stacking holder members.

5. In a walled materials handling pallet, the combination of a deck provided with walls, legs comprising spaced top and bottom members and laterally spaced inner and outer uprights integral therewith, the bottom members having downwardly facing stacking recesses therein, a locking dog pivotally mounted on one of the legs between the uprights thereof, a detent for holding said dog in retracted position, stacking holder members on said walls adapted to receive the legs of a superimposed pallet and provided with hooks facing in the same direction and with which the legs of a superimposed pallet may be engaged, at least one holder member of each pallet

being provided with means with which said locking dog may be engaged and thereby prevent disengagement of the legs from the hooks of said stacking holder members.

6. In a walled materials handling pallet, the combination of a deck provided with walls, legs comprising spaced top and bottom members and laterally spaced inner and outer uprights integral therewith, the bottom members having downwardly facing stacking recesses therein, a locking dog pivotally mounted on one of the legs between the uprights thereof, a detent for holding said dog in retracted position, stacking holder members on said walls adapted to receive the legs of a superimposed pallet and provided with hooks with which the legs of a superimposed pallet may be engaged, at least one holder member of each pallet being provided with means with which said locking dog may be engaged and thereby prevent disengagement of the legs from the hooks of said stacking holder members.

7. In a walled materials handling pallet, the combination of a deck provided with walls, legs having downwardly facing stacking recesses therein, and upwardly facing stacking holder members on said walls adapted to receive the legs of a superimposed pallet and provided with hooks facing in the same direction and with which the legs of a superimposed pallet may be slidably engaged, at least one leg of each pallet being provided with a locking dog engageable with a holder member thereby pre-

venting disengagement of the legs from the hooks of said stacking holder members.

8. In a walled materials handling pallet, the combination of a deck provided with walls, legs having downwardly facing stacking recesses therein, and stacking holder members on said walls adapted to receive the legs of a superimposed pallet and provided with upwardly projecting laterally facing hooks with which the legs of a superimposed pallet may be slidably engaged and disengaged, at least one leg of each pallet being provided with a locking dog engageable with a holder member thereby preventing sliding disengagement of all the legs from all of said stacking holder members when the locking dog is in holder member engaging position.
